Q.S. 2323

Charles Ballinger, of Pittsburgh, Pa.

Assignor to

"McC. Kee & Brothers" of the same place,
Letters Patent No. 2323 Dated May 22, 1866,
Design for a Goblet.

The schedule referred to in the Letters Patent and making part of the same.

To all whom it may concern:

Be it known that I, Charles Ballinger, of Pittsburgh, in the County of Alleghany, and State of Pennsylvania, have produced a new and original design for a Goblet, and I do hereby declare that the following is a full, clear, and exact description of the same, reference being had to the accompanying drawings making a part of this specification in which.

Figure 1. represents the goblet, in perspective.

Figure 2. represents a top plan thereof.

A. represents the base, B. the stem, and C. the bowl of the goblet.

The stem B. is many sided, with the corners or lines a, running down on to the base A, and running out thereon.

Where the stem and bowl are joined there are angular lines B, meeting in points c, which in looking down vertically into the bowl, as seen in figure 2. represent a star form.

The base of the bowl is divided into a series of long, sharp pointed pannels d, with a sunken centre e, the upper portion of the bowl being plain.

The ornamental portions, are mainly by sinking grooves or channels along their margins, or by the sunken channels themselves.

What I claim is the design for a goblet as shown and described.

Witnesses

August. C. Morrison,
C. Field.
